ATTORNEY.

UNITED STATES PATENT OFFICE.

ANDREW LINCOLN EATON, OF NEW YORK, N. Y.

DESIGN FOR A BELT-FASTENER PLATE.

SPECIFICATION forming part of Design No. 30,520, dated April 11, 1899.

Application filed February 23, 1899. Serial No. 706,600. Term of patent 7 years.

To all whom it may concern:

Be it known that I, ANDREW LINCOLN EATON, a citizen of the United States, residing in the city of New York, (Manhattan,) in the county and State of New York, have invented and produced a certain new and original Design for a Belt-Fastener Plate, of which the following is a specification, reference being had to the accompanying drawings, forming a part thereof, in which—

Figure 1 shows a face view of the plate, and Fig. 2 is a section taken on the line 2 2 in Fig. 1.

The plate is of a general rectangular form having oppositely-extending semicircular portions at each corner and an outwardly-projecting point at each end on the center line.

The leading feature of my design is the

contour above described, consisting of the straight parallel sides A, the semicircular swells A', arranged oppositely and extending outwardly, the points or projections A² on each end at the mid-width joined by easy curves A³ to the semicircular swells, and the holes a at the center of each of the latter. 25

I claim—

The design for a belt-fastener plate, herein shown and described.

In testimony that I claim the invention above set forth I affix my signature in presence of two witnesses. 30

A. LINCOLN EATON.
